UNITED STATES PATENT OFFICE.

RALPH F. KNIGHT, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,264,661.

Specification of Letters Patent. Patented Apr. 30, 1918.

Original application filed October 25, 1915, Serial No. 57,689. Divided and this application filed November 22, 1916. Serial No. 132,785.

To all whom it may concern:

Be it known that I, RALPH F. KNIGHT, a citizen of the United States, residing at Beverly, in the county of Essex and Commonwealth of Massachusetts, have invented certain Improvements in Sewing-Machines, of which the following description, in connection with the accompanying drawings, is a specification, like reference characters on the drawings indicating like parts in the several figures.

The invention relates to sewing machines such as may be used for finishing button-holes, and by which the thrum ends and stay cord are gathered in line and are stitched to the under face of the work between the ends of the buttonholes by blind stitches.

This application is a division of application Serial No. 57,689, filed October 25, 1915.

The object of the invention is to provide novel and improved means for adjusting the bender which bends the work into position for the passage of the needle therethrough, and to this end the invention comprises the features of construction and combinations of parts hereinafter described and set forth in the claims.

The invention will be readily understood from an inspection of the accompanying drawings and the following detailed description of the mechanism illustrated therein.

In the drawings, Figure 1 is an end elevation showing so much of a buttonhole finishing machine as is necessary to illustrate the application of the present invention thereto, and Figs. 2 and 3 are detail views showing the bender adjusting mechanism.

In the drawings the invention is shown as embodied in a buttonhole finishing machine having the same general construction and mode of operation as the machine shown and described in Patent No. 1,080,341, dated December 2, 1913. In this machine the sewing mechanism comprises a horizontally reciprocating and laterally movable needle 2 and a coöperating shuttle 4. The work is supported on a work support 6 above the path of the needle, and prior to each reciprocation of the needle is forced downward by a bender 8 into a recess 10 to bring a fold in the work into the needle path.

The bender is mounted in the front end

of the bender arm 12, and may be adjusted vertically by a screw 14, the lower part of which is provided with a left-hand thread engaging the bender while the upper part is provided with a right-hand thread engaging a boss on the bender arm. The screw is provided at its upper end with a knurled head 16 by which it may be manipulated in adjusting the bender. The bender is clamped in adjusted position by a clamping screw 18. The knurled head on the upper end of the bender is in the form of a split nut which is threaded on to the end of the screw and is secured in position by a clamping screw 20. With this construction the split nut may be so adjusted on the screw that it will strike the boss on the bender arm when the bender is in the lowest position in which it will operate properly with the needle. The knurled head may thus act as a stop for limiting the downward adjustment of the bender. When once adjusted, it is secured permanently in position by its clamping screw, which may be sealed or otherwise secured against improper release if found desirable.

While it is preferred to employ the specific construction and arrangement of parts shown and described, it will be understood that this construction and arrangement is not essential to the broader features of the invention, and may be varied or modified as found desirable or best suited to the construction of the machine in which the invention is to be embodied.

Having explained the nature and object of the invention, and specifically described one form of mechanism in which it may be embodied, what is claimed is:

1. A sewing machine, having, in combination, a work support, a bender, an arm on which the bender is mounted, a screw for adjusting the bender, and a split nut secured to the upper end of the screw to form a head by which the screw is manipulated in adjusting the bender.

2. A sewing machine, having, in combination, a work support, a bender, an arm on which the bender is mounted, a screw for adjusting the bender, and a split nut secured to the upper end of the screw and arranged to engage the arm and limit the downward adjustment of the bender.

3. A sewing machine, having, in combination, a work support, a bender, an arm on which the bender is mounted, a screw for adjusting the bender, a nut on the upper end of the screw to form a head by which the screw is manipulated in adjusting the bender, and means for securing the nut to the screw.
4. A sewing machine, having, in combina-

tion, a work support, a bender, an arm on which the bender is mounted, a screw for adjusting the bender, and a head adjustably secured to the upper end of the screw and arranged to engage the arm and limit the downward adjustment of the bender. 10

RALPH F. KNIGHT.
